United States Patent

Des. 239,613

Patented Apr. 20, 1976

239,613

SUBMARINE

Glen R. Askeborn, 90 Gerrish Ave.,
East Haven, Conn. 06512

Filed May 27, 1975, Ser. No. 580,958

Term of patent 14 years

Int. Cl. D12—06

U.S. Cl. D12—65

FIG-1

FIG-2

FIG-3

FIG-4

FIG-5

FIG-6

FIG. 1 is a perspective view of a submarine embodying my new design;

FIG. 2 is a front elevation of the submarine;

FIG. 3 is a right side elevation of the submarine, the right and left sides of the submarine being identical in ornamental appearance;

FIG. 4 is a rear elevation of the submarine;

FIG. 5 is a top plan view of the submarine; and

FIG. 6 is a bottom plan view of the submarine.

I claim:

The ornamental design for a submarine, as shown and described.
